DESIGN FOR A BROOCH PIN OR SIMILAR ARTICLE

Anne Glass, New York, N. Y.

Application December 16, 1940, Serial No. 97,345

Term of patent 3½ years

To all whom it may concern:

Be it known that I, Anne Glass, a citizen of the United States of America, residing in New York city, county of New York, and State of New York, have invented a new, original, and ornamental Design for a Brooch Pin or Similar Article, of which the following is a specification, reference being had to the accompanying drawing, forming part thereof, wherein,

I claim:

The ornamental design for a brooch pin or similar article, substantially as shown.

ANNE GLASS.
